ABSTRACT OF THE DISCLOSURE

An alarm device including detecting means producing an alarm signal in response to presence of a trespasser, a first alarm means for giving an alarm, a second alarm means for giving an alarm, said first alarm means connected to both said detecting means and said second alarm means, switching means in said first alarm means and said second alarm means completing a circuit for giving an alarm in response to the detecting means producing an alarm signal, severing connections between either the first alarm means and the detecting means or the first alarm means and the second alarm means, or vibration of either alarm means, and disabling means including at least one series of stationary contacts and a movable contact selectively engaging one of the stationary contacts.

This invention relates to an alarm device for objects to be protected such for example as a safe, and more particularly to an alarm device adapted to raise an alarm upon removal or shift of a conductive screen, door or the like, disposed opposite an object to be protected in the vicinity thereof, or of a switch mechanism mounted on the protected object.

It is one object of this invention to provide an alarm device which is capable of raising an alarm for the presence of a trespasser without attracting his attention.

It is another object of this invention to provide an alarm device which raises an alarm in response to the variations in electrical capacity established between a conductive plate-like member and an object to be protected, both being disposed in adjacent but opposing relation.

It is still another object of this invention to provide an alarm device which is adapted to raise an alarm upon shift or removal of a switch device mounted on an object to be protected.

Other objects, features and advantages of this invention will become apparent from the following description taken in conjunction with the accompanying drawings, in which:

FIG. 1 schematically illustrates relative connections and arrangements of an alarm device according to this invention;

FIG. 2 is a front view of a safe to which the device of this invention is attached;

FIG. 3 is a front view of a screen employed in the device of this invention;

FIG. 4 is a diagram schematically illustrating another example of the alarm device of this invention;

FIG. 5 is a connection diagram showing one example of the electrical system for the operation of the device illustrated in FIG. 4; and

FIGS. 6 to 8, inclusive, are connection diagrams similar to FIG. 5 and illustrating other examples of the electrical system for use with the alarm device of this invention.

With reference to the drawings the present invention will be described in detail. In FIG. 1, reference numeral 1 indicates an object to be protected such, for example, as a safe.

As illustrated in the figure, a screen 2 is positioned

2

adjacent the front or a door 1a of the safe 1 in opposing relation thereto. The front 1a of the safe 1 is made of a conductive material, namely the doors 3a and 3b are made of a conductive material and they are grounded as depicted in FIG. 2. The screen 2 has mounted thereon a conductive plate 4 on the side 2a opposed at least to the front doors 3a and 3b of the safe 1, as illustrated in FIG. 1. Further, the screen 2 has, for example, insulating wheels 5 so as not to be grounded. Reference numeral 2' indicates a supporting member for stably supporting the screen 2, which member has also insulating wheels 5. The screen 2 can be moved to a desired position at any time.

With such an arrangement, an equivalent capacitor is constituted between the front doors 3a and 3b of the safe 1 and the conductive plate 4 of the screen 2. Then, the capacitor thus constituted is connected to an alarm device, as illustrated in FIG. 1.

In FIG. 1, reference numeral 6 identifies a device including an oscillator, amplifier, and low-frequency amplifier. Reference numeral 7 indicates a parallel tuning circuit for determining the oscillation frequency of the oscillator.

The oscillator of the device 6 has a center frequency f_0 of, for example, 150 kc. and is adapted such that the oscillation frequency varies with the variations in the capacity of the parallel capacitor of the parallel tuning circuit, to thereby change the output of the parallel tuning circuit, to thereby change the output of the amplifier connected to the output side of the oscillator. Connected to the output side of the amplifier is a relay, which is switched on and off to actuate, for example, an alarm bell, buzzer and/or the like. Since it will be apparent to those skilled in the art that the constructions and interconnections of the aforementioned oscillator, amplifier, relay and alarm device may be of any desired ones, no detailed description will be given for the sake of brevity. However, a description will be given later, by way of example, in connection with the contacts of the alarm device actuated by the relay and the alarm device connected thereto. Reference numeral 8 designates an alarm circuit including an alarm bell or buzzer. Further, a terminal 9 of the oscillator 6 is connected through a line 9 to the conductive plate 4 of the screen 2.

Thus, the capacity established between the front doors 3a and 3b of the safe 1 and the conductive plate 4 of the screen 2 is incorporated in parallel with the tuning circuit 7. Accordingly, when a trespasser approaches, moves or touches the screen 2 or he puts one part of his body between the front doors 3a and 3b of the safe 1 and the screen 2, the oscillation frequency of the oscillator is caused to vary in response to the variations in the capacity established between the safe 1 and the screen 2, whereby an alarm is given. Meanwhile, breakage of the line 9 also causes capacity variations, to thereby give a warning.

The screen 2 is so designed as to have the appearance of a usual screen, so as not to attract one's specific attention when disposed in association with the alarm device for the object to be protected.

According to the present invention, since the screen can be positioned separately from an object to be protected, for example, a safe as described above, the present invention has an advantage that the screen can be freely used for an established safe against trespass of a thief.

The foregoing has been made in connection with the case where the screen has mounted thereon a conductive plate constituting capacity with the protected object, while the same results can be obtained by attaching a conductive plate to a door located in such a position as to provide capacity between the conductive plate and an object to be protected.

FIG. 4 is a schematic diagram illustrating another example of the alarm device of this invention, which is adapted to be switched on or off to raise an alarm upon movement of the safe or opening of its door. That is, an electrical warning circuit is constituted by the provision of a contact mechanism associated with dials. This warning circuit is designed to issue a warning upon incorrect dialing, opening of the door of a safe or breakage of a line of the circuits of the alarm device during the operative condition of the alarm device.

In FIG. 4 the reference numeral 101 identifies generally an alarm device of this invention. The alarm device 101 is provided with, for example, three dials D₁, D₂ and D₃ operable from the outside of the casting 101c of the device 101, a set switch S₁ for setting the alarm device in the operative condition which is preferred to be of a push-button type, a reset switch S₂ for resetting the device, a pilot lamp L₅ for indicating the operative condition of the device and alarm pilot lamps L₁ to L₄. The reference numeral 102 designates generally an object to be protected such, for example, as a safe which consists of a safe proper 102a and a door 102b and on which alarm signal generating devices P₁ and P₂, each constructed as a switch are mounted in such a manner as to extend on the safe proper 102a and the door 102b when the latter is closed. These generating devices P₁ and P₂ are designed to be switched on or off by shift, removal or breakage thereof, causing circuits including the generating devices to raise an alarm. In some cases, it is possible to mount the alarm signal generating devices P₁ and P₂ on a desired body which is located near the protected object and can readily be moved by a trespasser. Further, a similar alarm signal generating device P₃ and coupling member U₇' are similarly mounted on the casing 101c of the alarm device 101, and the coupling member U₇' is connected with the lines l₁ to l₆ through lines l₂₀ to l₂₃. With such an arrangement, if a trespasser tries to break the casing 101c, the alarm signal generating device P₃ is moved out of position by shock to thereby actuate the contact S_{3a} or S_{3b}. Accordingly, since the relay R₈ is actuated prior to the breakage of the casing 101c, the sub-unit 103 is actuated to raise an alarm in the same manner as that described later. By the provision of a similar alarm signal generating device on casing 103c of the sub-unit, the alarm device 101 can be likewise actuated prior to breakage of the sub-unit.

The sub-unit can be placed at a remote location from the alarm unit 101.

The alarm signal generating device P₁ and P₂ mounted on the safe 102 and the alarm device 101 are interconnected through lines l₁ to l₆, while the alarm unit 101 and the sub-unit 103 are also interconnected through lines l₇ to l₁₂. U₁ and U₂ indicate coupling members such, for example, as plus provided on the alarm unit 101. U₁' and U₂' designate similar coupling members provided on the devices P₁ and P₂ mounted on the safe 102. The alarm signal generating devices P₁ and P₂ mounted on the safe 102 and the alarm device 101 are interconnected by respectively coupling the coupling members U₁ and U₂ of the device 101 and those U₁' and U₂' of the safe 102 through the lines l₁ to l₆. U₃, U₄ and U₅ are like coupling members provided on the alarm device 101 and U₃', U₄' and U₅' are also coupling members mounted on the sub-unit 103. The alarm device 101 and the sub-unit 103 are interconnected by coupling the coupling members U₃, U₄ and U₅ of the former and those U₃', U₄' and U₅' of the latter through the lines l₇ to l₁₂ in three pairs.

With such an arrangement, an alarm will not be produced through removal of the alarm signal generating devices P₁ and P₂ from the safe 102 and opening of the door 102b thereof only when the dials D₁, D₂ and D₃ are in the correct dial positions but in the incorrect positions an alarm will be raised by the alarm device 101 and the sub-unit 103.

Referring now to FIG. 5, the construction and opera-

tion of the alarm device will hereinafter be described in detail.

In FIG. 5 similar components to those in FIG. 4 are identified at the same reference numerals. The alarm signal generating devices P₁ and P₂ have normally open contacts S_{3a}, S_{4a} and normally closed contacts S_{3b}, S_{4b} respectively.

The alarm device 101 includes relays R₁ to R₈, an alarm bell B₁, the aforementioned dials D₁, D₂ and D₃, three contact mechanisms W_{1a}, W_{2a} and W_{3a}, three other similar contact mechanisms W_{1b}, W_{2b} and W_{3b} and a power source E₁. The contact mechanisms W_{1a}, W_{2a} and W_{3a} respectively consist of movable contacts ω_{1a0} , ω_{2a0} and ω_{3a0} associated with the shafts of the dials D₁, D₂ and D₃ and three groups of twelve stationary contacts (ω_{1a1} , ω_{1a2} , . . . ω_{1a12}), (ω_{2a1} , ω_{2a2} , . . . ω_{2a12}) and (ω_{3a1} , ω_{3a2} , . . . ω_{3a12}) in cooperating relation to the movable contacts ω_{1a0} , ω_{2a0} and ω_{3a0} . In a similar manner, the contact mechanisms W_{1b}, W_{2b} and W_{3b} respectively consist of movable contacts ω_{1b0} , ω_{2b0} and ω_{3b0} and three group of twelve stationary contacts (ω_{1b1} , . . . ω_{1b12}), (ω_{2b1} , . . . ω_{2b12}) and (ω_{3b1} , . . . ω_{3b12}) in cooperating relation to the movable contacts ω_{1b0} , ω_{2b0} and ω_{3b0} . If now the dial code number of the alarm device 101 is, for example, 263, the movable contacts ω_{1b0} , ω_{2b0} and ω_{3b0} of the contact mechanisms W_{1b}, W_{2b} and W_{3b} are in contact with their respective stationary contacts ω_{1b2} , ω_{2b6} and ω_{3b3} .

The sub-unit 103 includes relays R₉ to R₁₁, an alarm bell B₂ and a power source E₂.

In FIG. 5 the alarm device has been set in the operative condition and the set switch S₁ is kept closed. In this case the normally open contact r_{7b} of the relay R₇ remains open, so that the relay R₇ is not energized and its normally closed contact r_{7a} remains closed. Accordingly, the lamp L₅ is lighted by the power source E₁ through a closed circuit of the power source E₁—the normally closed contact r_{7a} of the relay R₇—the lamp L₅—the power source E₁, thus indicating that the alarm device is in its operative condition. The other lamps L₁ to L₄ are all held turned off, which will be seen from the figure.

Under such conditions, removal of the signal generating device, for example, P₁ will lead to closing of the contact S_{3a} to thereby constitute a closed circuit of the power source E₁—the coupling member U₁—the line l₁—the coupling member U₁'—the contact S_{3a}—the coupling member U₁'—the line l₃—the coupling member U₁—the relay R₁—the power source E₁, thus the relay R₁ being energized by the power source E₁. Accordingly, normally open contacts r_{1a} , r_{1b} , and r_{1c} are closed with energization of the relay R₁. This provides a closed circuit of the power source E₁—the contact r_{1c} of the relay R₁—the bell B₁—a normally closed contact r_{7d} of the relay R₇—the power source E₁, through which the bell B₁ is energized by the power source E₁ to sound an alarm. At the same time, there is constituted a closed circuit of the power source E₁—the lamp L₁—the contact r_{1b} of the relay R₁—the power source E₁, turning on the lamp L₁ to indicate issuance of the alarm. The energization of the relay R₁ further establishes a closed circuit of the power source E₁—a normally closed contact r_{7c} of the relay R₇—a contact r_{1a} of the relay R₁—the relay R₁—the power source E₁. This causes the relay R₁ to be self-maintaining, thereby holding the alarm bell and bell in their operative condition.

Meanwhile, removal of the other alarm signal generating device P₂ from the safe 2 will lead to closing of the contact S_{4a} and energization of the relay R₂ by the power source E₁ in the same manner as that in the case of closing the contact S_{3a}. This results in closing of normally open contacts r_{2a} , r_{2b} and r_{2c} of the relay R₂ and provides closed circuits respectively. That is, the bell B₁ is rung, the lamp L₂ is lighted and a self-maintaining circuit of the relay R₂ is constituted in the same manner as that in the case of the device P₁.

Upon removal of the alarm signal generating device P_1 , a normally closed contact S_{3b} is opened and also in this case the bell B_1 is rung and the lamp L_4 is lighted. That is, the opening of the contact S_{3b} leads to cutting off a closed circuit of the power source E_1 —the coupling member U_1 —the line l_1 —the coupling member U_1' —the contact S_{3b} —the coupling member U_1' —the line l_2 —the coupling member U_1 —the relay R_4 —the power source E_1 , thus making the relay R_4 inoperative. This results in closing of its normally open contacts r_{4a} , r_{4b} and r_{4c} and provides closed circuits respectively. As a result of this, the bell B_1 is rung through a closed circuit of the power source E_1 —the contact r_{4c} of the relay R_4 —the bell B_1 —the contact r_{7d} —the power source E_1 , while the lamp L_4 is lighted through a closed circuit of the power source E_1 —the lamp L_4 —the contact r_{4b} of the relay R_4 —the power source E_1 .

Upon removal of the alarm signal generator P_2 , a contact S_{4b} is opened to make the relay R_5 inoperative, in a manner similar to that just described above in the removal of the generator P_1 , and its normally open contacts r_{5a} , r_{5b} and r_{5c} are thereby closed. Thus, the bell B_1 is rung through the contact r_{5c} and the lamp L_4 is lighted through the contact r_{5b} .

Even if the contact S_{3a} or S_{4a} is not closed upon removal of the alarm signal generating device P_1 or P_2 , opening of the contact S_{3b} or S_{4b} leads to de-energization of the relay R_4 or R_5 , which causes the contact r_{4a} or r_{5a} to close. This provides a closed circuit of the power source E_1 —the contact r_{4a} or r_{5a} —the relay R_1 or R_2 —the power source E_1 . As a result of this, the relay R_1 or R_2 is energized by the power source E_1 and the same results can be obtained as those with the closing of the contact S_{3a} or S_{4a} .

Further, since the relay R_8 is connected in parallel with a series circuit of the bell B_1 and the normally closed contact r_{7d} , the relay R_8 is also energized when the bell B_1 rings. With energization of the relay R_8 , its normally open contact r_8 is closed and consequently the coupling members U_5 and U_5' are electrically connected. As a result of this, there is constituted in the sub-unit 103 a closed circuit of the power source E_2 —the relay R_{10} —the coupling member U_5' —the line l_{12} —the coupling member U_5 —the contact r_8 of the relay R_8 —the coupling member U_5' —the line 11—the coupling member U_5' —a normally closed contact r_{9c} of the relay R_9 —the power source E_2 . With this closed circuit the relay R_{10} is energized to thereby close its normally open contacts r_{10a} and r_{10b} .

Consequently, there is constituted a closed circuit of the power source E_2 —the contact r_{10a} of the relay R_{10} —a normally closed contact r_{9b} of the relay R_9 —the alarm bell B_2 —the power source E_2 , thus energizing the bell B_2 to sound an alarm. In this case, the relay R_{10} is self-maintained by a closed circuit of the power source E_2 —the relay R_{10} —the contact r_{10b} —the contact r_{9c} —the power source E_2 , so that the bell B_2 is caused to go on with sounding an alarm.

Thus, protection of, for example, a safe from a trespasser can be accomplished by raising an alarm in a manner described above.

Now, a description will be given in connection with cancellation of an alarm produced as has been described in the foregoing. For this purpose, the movable contacts ω_{1a0} , ω_{2a0} and ω_{3a0} of the contact mechanisms W_{1a} , W_{2a} and W_{3a} associated with the shafts of the dials D_1 , D_2 and D_3 are turned into contact with the stationary contacts ω_{1a2} , ω_{2a6} and ω_{3a3} respectively. Then, the reset switch S_2 is pressed, which results in the provision of a closed circuit of the power source E_1 —the relay R_7 —the contact ω_{3b0} of the contact mechanism W_{3b} —the contact ω_{3b3} —the contact ω_{3a3} of the contact mechanism W_{3a} —the contact ω_{3a0} —the contact ω_{2b0} of the contact mechanism W_{2b} —the contact ω_{2b6} —the contacts ω_{2a6} of the contact mechanism W_{2a} —the contact ω_{2b0} —the contacts ω_{1b0} of the contact mechanism W_{1b} —the contact ω_{1b2} —the

contact ω_{1a2} of the contact mechanism W_{1a} —the contact ω_{1a0} —the switch S_2 —the power source E_1 . The relay R_7 is thereby energized, which leads to opening of the normally closed contact r_{7d} of the relay R_7 inserted in series with the bell B_1 to thereby stopping the ringing of the bell B_1 . At the same time, the normally closed contact r_{7c} of the relay R_7 is opened which is incorporated in series with the self-maintaining circuits of the relays R_1 and R_2 .

10 Namely, the relays R_1 and R_2 are made inoperative to put off the lamps L_1 and L_2 . However, the lamp L_4 remains on so long as the contact S_{3b} or S_{4b} is held open.

Upon energization of the relay R_7 , its normally closed contact r_{7a} is also opened to thereby cut off the closed circuit of the power source E_1 —the contact r_{7a} —the lamp L_5 —the power source E_1 , while the relay R_7 is incorporated into a closed circuit of the power source E_1 —the relay R_7 —the switch S_1 —the normally open contact r_{7b} of the relay R_7 —the power source E_1 , so that the relay 15 R_7 is caused to be self-maintaining.

Meanwhile, the relay R_9 is energized by a closed circuit of the power source E_1 —the coupling member U_4 —the line l_9 —the coupling member U_4' —the relay R_9 —the coupling member U_4' —the line l_{10} —the coupling member U_4 —the switch S_1 —the contact r_{7b} —the power source 25 E_1 . The energization leads to opening of its normally closed contacts r_{9b} and r_{9c} . This results in stopping the bell B_2 and in cutting off the self-holding circuit of the relay R_{10} . In this manner, cancellation of an alarm once 30 produced can completely be carried out.

From the foregoing it appears that with the dials D_1 , D_2 and D_3 in the correct positions, opening of the safe will not lead to ringing of the bells B_1 and B_2 and to lighting of the lamps L_1 and L_2 . That is, an alarm will not be raised unnecessarily.

The foregoing description has been made in connection with the operations of the alarm device resulting from removal of the alarm signal generating devices P_1 and P_2 from the safe 102. However, pulling out any one of the coupling member U_1 , U_2 , U_1' and U_2' will produce the same results as those by the opening of the normally closed contacts S_{3b} or S_{4b} , and hence an alarm will be given in the manner described above. Further, cancellation of thus produced alarm is exactly the same as in the foregoing. Breakage of the lines l_1 , l_2 , l_4 and l_5 will yield the same results.

Meanwhile, breakage of the lines l_7 and l_8 between the alarm device 101 and the sub-unit 103 will lead to opening of a closed circuit of the power source E_1 —the coupling member U_3 —the line l_7 —the coupling member U_3' —the normally closed contact r_{11a} of the relay R_{11} —the coupling member U_3 —the line l_8 —the coupling member U_3' —the relay R_6 —the power source E_1 . Hence, the relay R_6 is deenergized and its contacts r_{6a} , r_{6b} and r_{6c} are closed. That is, there are established a closed circuit of the power source E_1 —the contact r_{6c} of the relay R_6 —the bell B_1 —the contact r_{7d} —the power source E_1 , another closed circuit of the power source E_1 —the lamp L_4 —the contact r_{6d} —the power source E_1 and still another closed circuit of the power source E_1 —the contact r_{6a} —the relay R_3 —the power source E_1 . Thus, the lamp L_4 is turned on and the bell B_1 is rung and the relay R_3 is energized. The energization of the relay R_3 provides a closed circuit of the power source E_1 —the contact r_{3c} —the bell B_1 —the contact r_{7d} —the power source E_1 , another closed circuit of the power source E_1 —the lamp L_3 —the contact r_{3b} —the power source E_1 and still another closed circuit of the power source E_1 —the contact r_{7c} —the contact r_{3a} —the relay R_3 —the power source E_1 . Thus, the bell B_1 is rung, the lamp L_3 is lighted and the relay R_3 is self-maintained to hold the bell B_1 and the lamp L_3 in operation. At the same time, the relay R_8 is actuated to thereby ring the bell B_2 of the sub-unit 103 as described previously. The alarm thus

raised can be cancelled in the same manner as the aforementioned.

Further, it is possible to design the alarm device such that the bells and the lamps are actuated upon breakage of the alarm device 101. For this purpose, it is sufficient only to insert between the lines l_1 and l_3 or between those l_4 and l_6 a switch S_{1a} or S_{2a} which is adapted to be closed by vibration. That is, the switches S_{1a} and S_{2a} equivalently perform the function of the switches S_{3a} and S_{4a} , yielding the same results as those described previously.

Also in the sub-unit 103, a similar switch S_5 is provided which is adapted to be closed by, for example, vibration. Upon closing of the switch S_5 , there is constituted a closed circuit of the power source E_2 —the relay R_{11} —the switch S_5 —the contact r_{9c} —the power source E_2 . The relay R_{11} is energized by this closed circuit and this provides in turn a closed circuit of the power source E_2 —a contact r_{11b} of the relay R_{11} —the contact r_{9b} —the bell B_2 —the power source E_2 , through which the bell B_2 is energized to sound an alarm. At the same time, there is provided another closed circuit of the power source E_2 —the relay R_{11} —its contact r_{11c} —the contacts r_{9a} of the relay R_9 —the contact r_{9c} of the relay R_9 —the power source E_2 , thus constituting a self-holding circuit for the relay R_{11} . Removal of the alarm is exactly the same as that described previously. Namely, the relay R_9 is actuated to open its contact r_{9a} , cutting off the self-holding circuit of the relay R_{11} .

In order to change the dial code numbers, it is sufficient only to change the contact positions of the movable contacts ω_{1b0} , ω_{2b0} and ω_{3b0} of the contact mechanisms W_{1b} , W_{2b} and W_{3b} .

When the dials have been made to assume the correct positions as described above, the self-loading circuit of the relay R_7 is constituted. Accordingly, re-setting of the device in the operative condition requires only pressing of the switch S_1 and turning of the dials out of the correct positions. In this manner, the device is set again in the initial condition thereof.

In this case, however, there is the possibility that the set switch S_1 is left unpressed, even if the dials are turned out of the correct positions without fail. To avoid this, a contact mechanism W_{4a} is provided which interlocks with the shaft of, for example, the dial D_3 and is similar to the contact mechanism, for instance, W_{3a} , as illustrated in FIG. 6. In this case, the switch S_1 is left out and the contact mechanism W_{4a} is disposed in the position of the switch S_1 . In this case, it is required to remove the connecting line of at least one of the stationary contacts of the contact mechanism W_{4a} . That is, if the dial code number of the dial D_3 is 3, the connecting line of the stationary contact, for example, ω_{4a7} other ω_{4a3} of the contact mechanism W_{4a} must be eliminated. In such a case, at least when the dial D_3 is in the correct position, the self-maintaining circuit of the relay R_7 is formed. Upon setting, the movable contact ω_{4a0} passes the position of the contact ω_{4a7} in turning the dial D_3 out of the correct position, so that the same results as those by pressing of the switch S_1 can be obtained. That is, the alarm device is set in the operative condition without annoying the aforementioned disadvantage resulting from the provision of the switch S_1 .

It is also possible to adapt the alarm device such that unnecessary pressing of the reset switch S_2 will cause the bells to ring and the lamps to light. This can be accomplished by the provision of a normally open switch S_2' which interlocks with the switch S_2 . As illustrated in FIG. 7, the switch S_2' is inserted in parallel with the switch S_{1a} of the circuit illustrated in FIG. 5. In this case, however, pressing of the switches S_2 and S_2' causes the bell to ring even when the dials are in the correct positions. To avoid this, the alarm device is designed in the following manner. That is, the set lamp L_5 is not put off and no bell is rung by a first pressing of the switch S_2 when the dials are in the incorrect positions. In this case, lighting of the lamp L_5 indicates that the dials are

in the incorrect positions. Once the dials have been made to be in the correct positions, pressing of the switches leads to putting out the lamp L_5 without ringing any of the bells. On the other hand, when the switch is pressed twice without turning the dials in the correct positions, the bell is rung.

To accomplish this, the parallel connection of the switch S_2' with the switch S_2 is left out. As shown in FIG. 8, there is provided by pressing of the switch S_2' a closed circuit of the power source E_1 —the normally closed contact r_{7d} of the relay R_7 —the switch S_2' —the relay R_{12} —the power source E_1 , thus energizing the relay R_{12} . The energization of the relay R_{12} provides a closed circuit of the power source E_1 —the contact r_{7d} —a contact r_{12a} of the relay R_{12} —a relay R_{13} —the power source E_1 , so that the relay R_{13} is energized. As a result of this, there is formed a closed circuit of the power source E_1 —the contact r_{7d} —a contact r_{12b} of the relay R_{12} —a relay R_{14} —a contact r_{13a} of the relay R_{13} —the power source E_1 , and hence the relay R_{14} is energized. Meanwhile, the relay R_{13} is self-held through a closed circuit of the power source E_1 —the contact r_{7d} —the contact r_{13b} —the relay R_{13} —the power source E_1 . This provides a closed circuit of a terminal T_1 connected in parallel to the switch S_{1a} —the contact r_{12c} of the relay R_{12} —the contact r_{14a} of the relay R_{14} —a terminal T_2 . On the other hand, the relay R_{14} is made to be self-holding through a closed circuit of the power source E_1 —the contact r_{7d} —the contact r_{14b} —the relay R_{14} —the contact r_{13a} —the power source E_1 . In such a case, if the dials are not in the correct positions in a first pressing of the switches S_2 and S_2' , the relay R_7 is not energized as described above, so that the lamp L_5 remains on, indicating that the dials are in the incorrect positions. At this time, since no self-holding circuit is provided for the relay R_{12} , its contact r_{12c} immediately returns to its initial position after pressing of the switches. This cuts off the line between the terminals T_1 and T_2 and the closed circuit of the relay R_1 is not formed, so that the bell B_1 is not rung.

Upon pressing the switches S_2 and S_2' after the dials have been made to assume the correct positions, the relay R_7 is energized to open its contact r_{7d} as described previously. Therefore, the relay R_{12} is not energized again and its contact r_{12c} remains open, so that no bells ring. If the switches S_2 and S_2' are pressed again with the dials in the incorrect positions after the aforementioned first pressing, the relay R_{12} is energized again because the relay R_7 is not energized to keep its contact r_{7d} closed. Accordingly, the line between the terminals T_1 and T_2 are completed through the contact r_{12c} , and hence a closed circuit of the relay R_1 is formed through the terminals T_1 and T_2 . (This is the same condition as that obtained in the case where the switches S_{3a} and S_{1a} are closed.) As a result of this, the bell is sounded.

The connections shown in FIGS. 5 to 8 may be employed as the alarm device 8 of the example shown in FIG. 1. That is, the contact S_{3a} or S_{3b} (S_{4a} or S_{4b}) shown in FIGS. 5 to 8 is utilized as a contact of a relay connected to the output side of the amplifier in the circuit 6.

Although the present invention has been described with reference to a safe, the principles of this invention can be applied to any other desired object to be protected. Further, the alarm signal generating device may be those which function in the manner of a switch.

It will be apparent that many modifications and variations may be effected without departing from the scope of the novel concepts of this invention.

What I claim is:

1. An alarm device comprising:
detecting means having at least a normally closed switch opening in response to a trespasser disturbing an object to be protected;
a first alarm circuit having a first electric power source connected in parallel with an alarm producing means,

a first, a second and a third switch actuator, and also having a fourth switch actuator connected in parallel across said alarm producing means; first housing means generally enclosing said first alarm circuit;

a first vibration-sensitive switch mounted on said first housing and having a normally open pair of contacts closing in response to vibration of said first housing means;

a second alarm circuit having a second electric power source connected in parallel with a second alarm producing means, a fifth switch actuator and a sixth switch actuator;

second housing means generally enclosing said second alarm circuit;

a second vibration-sensitive switch mounted on said second housing means and having a pair of normally open contacts closing in response to vibration of said second housing means;

said first alarm circuit including

a first series circuit connected in series with said first switch actuator and including said normally closed detecting switch, a first lead line extending between said detecting switch and said first electric power source and a second lead line extending between said detecting switch and said first actuator so that said first actuator is normally operated,

a second series circuit connected in series between said electric power source and said second switch actuator and including a normally closed switch disposed in said second housing means and opening in response to actuation of said fifth switch actuator, a third lead line extending between said last mentioned normally closed switch and said second switch actuator and a fourth lead line extending between said first electric power source and said last mentioned normally closed switch,

a first parallel circuit connected in series between said third switch actuator and said electric power source and including said normally open contacts of said first vibration-sensitive switch and a normally closed switch actuated by said first switch actuator,

a second parallel circuit connected in series between said power source and said alarm producing means and including a second normally closed switch actuated by said first switch actuator, a normally closed switch actuated by said second switch actuator and a normally open switch actuated by said third switch actuator;

said second circuit including

a normally opened switch disposed in said first housing means and actuated by said fourth switch actuator and connected in series between said second power source and said sixth switch actuator,

said normally opened pair of contacts of said second vibration-sensitive switch connected in series between said second power source and said fifth switch actuator, and

a third parallel circuit connected in series between said second power source and said second alarm producing means and including two pairs of normally open contacts respectively actuated by said fifth and said sixth switch actuators,

whereby a circuit is completed between said first power source and said first alarm producing means whenever the object to be protected is disturbed in a manner to open said normally closed detecting switch, said first housing means is disturbed to close the normally open pair of contacts of said first vibration-sensitive switch, any one of said first, said second, said third or said fourth lead lines are severed, or said second housing means is

disturbed in a manner to close said normally open pair of contacts of said second vibration-sensitive switch and a circuit is completed between said second power source and said second alarm producing means whenever said second housing means is disturbed in a manner to close said normally open pair of contacts of said second vibration-sensitive switch means or said fourth switch actuator is actuated, i.e. whenever a circuit is completed between said first power source and said first alarm producing means.

5 2. An alarm device as defined in claim 1 and further characterized by:

said detecting means comprising an oscillator having an L-C tuning circuit and a conductive member disposed in opposing relation to the object to be protected and establishing a capacitance in parallel with the capacitor of the tuning circuit of said oscillator, and means opening said normally closed detecting switch whenever the capacitance established between the object to be protected and the conductive member varies due to the presence of a trespasser.

10 3. An alarm device as defined in claim 1 and further characterized by:

said detecting means comprising an alarm signal generating means detachably mounted on the object to be protected and opening said normally closed detecting switch whenever said alarm signal generating means are moved.

15 4. An alarm device as defined in claim 1 and further characterized by:

means for opening a pair of normally closed switches respectively connected in series between said first power source and said first alarm producing means and between said second power source and said second alarm producing means and including an encoded permutation circuit having

20 a plurality of stationary contacts,

a movable contact selectively engaging one of said stationary contacts, and

a seventh switch actuator for opening said last mentioned two pairs of normally closed contacts and connected in series between said first power source and a selected one of said stationary contacts.

25 5. An alarm device as defined in claim 1 and further characterized by:

a holding circuit for said third switch actuator and including a pair of normally open holding contacts actuated by said third switch actuator and connected in parallel with said first parallel circuit; and

30 a holding circuit for said sixth switch actuator and including a pair of normally open holding contacts actuated by said sixth switch actuator and connected in parallel with said first parallel circuit.

35 6. An alarm device as defined in claim 5 and further characterized by:

circuit means for cancelling an alarm produced by said alarm producing means and for resetting said alarm circuits, said means comprising:

40 encoded permutation switch means having a plurality of stationary contacts and a movable contact for engaging said stationary contacts,

45 seventh switch actuating means connected in series with a selected one of said stationary contacts and said movable contact,

50 a manually operated, normally open reset switch connected in series with said seventh switch actuating means,

55 four pairs of normally closed contacts respectively connected in series with said first alarm producing means, said second alarm producing means, said first switch actuator holding contacts and said sixth switch actuator holding contacts,

60

65

70

75

11

whereby whenever said movable contact engages the selected one of said stationary contacts and said reset switch is closed, said seventh switch actuator opens all said pairs of normally closed contacts to cancel the alarm and reset the alarm circuits.

7. An alarm device as defined in claim 6 and further characterized by:

a pair of normally open holding contacts for said seventh switch actuator connected in parallel with said cancelling and resetting circuit means and actuated by said seventh switch actuator.

8. An alarm device as defined in claim 7 and further characterized by:

a manually operated, normally closed set switch connected in series with said holding contacts for said seventh switch actuator.

9. An alarm device as defined in claim 7 and further characterized by:

said switch means connected in series with said seventh switch actuator and said holding contacts for said seventh switch actuator, said means comprising

a plurality of stationary set contacts,

a movable set contact for engaging said stationary set contacts and being mechanically connected to said first mentioned movable contact for movement therewith,

at least one of said stationary set contacts, other

5 whereby, moving said movable cancelling contact, and thus said movable set contact, out of engagement with the selected one of said stationary cancelling contacts breaks a circuit actuating said seventh switch actuator, thereby automatically resetting said alarm circuits.

10

12

than one of said set contacts engaged by said movable set contacts when said movable cancelling contact engages the selected one of said stationary cancelling contacts, being disconnected from said circuit,
